UNITED STATES PATENT OFFICE.

FRED W. YOUNG, OF LONG ISLAND CITY, NEW YORK, ASSIGNOR TO WESTERN ELECTRIC COMPANY, INCORPORATED, OF NEW YORK, N. Y., A CORPORATION OF NEW YORK.

CARRIER-WAVE RECEIVING SYSTEM.

Application filed August 24, 1921. Serial No. 495,054.

To all whom it may concern:

Be it known that I, FRED W. YOUNG, a citizen of the United States, residing at Long Island City, in the county of Queens, State of New York, have invented certain new and useful Improvements in Carrier-Wave Receiving Systems, of which the following is a full, clear, concise, and exact description.

10 This invention relates to carrier wave receiving systems and more particularly to demodulating circuits.

The principal object of the invention is to provide a circuit such that demodulators 15 of different kinds may be used without substantial change in the circuit itself.

A feature of the invention consists in providing a crystal or other rectifying demodulator with a base member adapted to 20 cooperate with the socket member of a three-element thermionic demodulator.

According to this invention, the receiving circuit is provided with a demodulator socket adapted to cooperate with the ordinary three-element thermionic demodulator. When such a demodulating element is fitted into this socket, it will be properly 25 connected to have the incoming energy applied to its input circuit and to have cathode heating current and space current supplied 30 to the demodulating element itself. A demodulator of another type such as the well-known crystal rectifier may be mounted on a base member adapted to cooperate with 35 this same socket. If because of failure of the thermionic detector or the associated sources of heating and space current it is desired to use the simpler demodulator, the thermionic demodulator may be removed 40 and the rectifying demodulator substituted therefor.

The invention will best be understood by reference to the drawing in which Fig. 1 illustrates the schematic diagram of a radio 45 receiving system for receiving and demodulating high frequency waves; Fig. 2, a crystal or other rectifying demodulator; Fig. 3, the effective circuit of Fig. 1 with the demodulator of Fig. 2; Fig. 4, a three- 50 element thermionic demodulator; Fig. 5, the effective circuit of Fig. 1 with the demodulator of Fig. 4; Fig. 6, a radio receiving arrangement similar to Fig. 1, but

slightly modified; Fig. 7, a diagram of a rectifying demodulator; Fig. 8, the effective 55 circuit when the demodulator of Fig. 7 is associated with the circuit of Fig. 6; Fig. 9, a three-element thermionic demodulator; Fig. 10, the effective circuit when the demodulator of Fig. 9 is used with the circuit 60 arrangement of Fig. 6 and Figs. 11 and 12 show the base and socket of the demodulator of Fig. 7 in side and end elevation respectively.

Referring to Fig. 1, receiving antenna 1 is inductively connected by means of transformer 2 to a tuned circuit 3 including the secondary winding of the transformer 2 and a variable tuning condenser 4. A demodulator socket D of the well-known type used 70 for the three-element thermionic demodulator is provided with terminals G, P, F — and F +. The terminal G is connected to a terminal of condenser 4 through a stopping condenser 5 and the terminal F — 75 is directly connected to the other terminal of condenser 4. An extremely high resistance R is shunted across the input terminals of device D. Connected to the output terminals P and F — is the output circuit including in series source E_B and a receiver or other translating device 6. A two-way switch 7 permits source E_B to be cut out of the circuit if desired. Source E_A is connected in series with the regulating resistance 8 between the terminals F + and F —. The demodulator socket D is provided with four contact strips, g, p, f₁ and f₂, which are directly connected electrically with terminals G, P, F + and F —, respectively. 85

Fig. 2 shows a diagram of an ordinary crystal or other two-element demodulator adapted to cooperate with the circuit of Fig. 1. This demodulating element has two active contact terminals, g₁ and p₁ and two dummy contact terminals, f₃ and f₄, adapted to contact respectively with the contact strips f₁ and f₂ of element D. The insertion of the demodulator of Fig. 2 in the socket member D of the Fig. 1 circuit produces effectively 100 the circuit arrangement of Fig. 3. In this arrangement high frequency oscillations received by antenna 1 are supplied to the circuit 3, tuned to the frequency of these oscillations, from which they are impressed 105 through the condenser 5 upon the rectifying

demodulator to yield low frequency waves in the circuit of receiver 6. If desired, switch 7 may be thrown to eliminate source E_B from the circuit, but this is in general 5 unnecessary.

Fig. 4 illustrates diagrammatically a demodulator of the three-element thermionic type having its contact terminals marked in the same manner as those of the demodulator 10 of Fig. 2. When this demodulating element is inserted in the socket D of the circuit arrangement of Fig. 1, the circuit effectively reduces to the arrangement of Fig. 5 in which oscillations are supplied by tuned circuit 3 to the input circuit of a thermionic demodulator to produce low frequency indications in the receiver 6 in the output circuit of the demodulator. This is a well-known vacuum tube circuit commonly used 15 in demodulating high frequency oscillations.

As is well known, the base member of a thermionic demodulator is ordinarily provided with a bayonet pin in order to insure that the proper connections are made between the contacts of the demodulating device and the contactor strips of the socket. In the circuit arrangement of Fig. 6, the socket member D is provided with an extra contactor strip 10 which engages the bayonet 25 pin and is directly connected to a point between the negative terminal of source E_B and translating device 6.

Fig. 7 shows a diagram of an ordinary crystal or other two-element demodulator 30 adapted to cooperate with the circuit of Fig. 6. This demodulating element has two active contact terminals, g_1 and f , and a connection is also taken from terminal g_1 to the tip t of the bayonet pin 13. The insertion 35 of the demodulator of Fig. 7 in the socket D of the Fig. 6 circuit produces effectively the circuit arrangement of Fig. 8. It may be noted that in this circuit arrangement the resistance element R is connected in shunt 40 to the demodulating element, but its impedance is so extremely high that it has little or 45 no effect upon the response obtained in the receiver 6.

Fig. 9 shows a diagram similar to that of 50 Fig. 4 of a thermionic demodulator adapted to cooperate with the socket D of the Fig. 6 circuit to produce effectively the circuit arrangement of Fig. 10.

Fig. 11 shows a detail of a portion of the 55 demodulator of Fig. 7. In this arrangement, the socket member D is provided with a resilient contact member 10 insulated from the other contactor strips of the base and electrically connected with the negative terminal 60 of the space current source. The base member 12 of the detecting element is provided with the usual bayonet pin 13 which cooperates with bayonet slot 14 as shown in Fig. 12. The bayonet pin carries a contact- 65 ing tip t which is preferably electrically in-

sulated from the pin as a whole, but is directly connected to the contactor g_1 as indicated in Fig. 7.

What is claimed is:

1. A demodulator element having a base 70 and terminal contacts mounted thereon, a socket member having means for electrically engaging said contacts to complete circuits for said demodulator element, a projecting pin on said base member, one of said terminal contacts being carried thereby, and a bayonet slot in said socket member cooperating with said projecting pin to lock said base in said socket member. 75

2. A demodulator element having a base and terminal contacts mounted thereon, a socket member having means for electrically engaging said contacts to complete circuits for said demodulator element, a projecting pin on said base member, one of said terminal contacts being carried thereby, and a bayonet slot in said socket member cooperating with said projecting pin to lock said base in said socket member and a spring in 80 front of said slot for making electrical connection to said pin. 85

3. A radio receiving system comprising an antenna, an input circuit coupled to said antenna, an output circuit including a receiving device, means for interposing between said circuits a demodulating element comprising a base portion having contacts, one of said contacts projecting radially therefrom, said means comprising a socket having a tubular portion, a bayonet slot in 90 said tubular portion and means for making electrical connection to said projecting pin when said element is inserted in said socket. 95

4. In a radio receiving system the combination with a socket of a demodulating device having a base and terminal contacts thereon, one of said contacts comprising a radially projecting pin, said socket comprising a base portion having an opening therein, a tubular portion fitted in said opening and arising therefrom, a plurality of contact springs secured to but insulated from said base, said springs projecting under the base portion and beneath said opening and so disposed as to make connection with certain of the contacts on the said demodulating device in a prearranged manner and an additional contact spring arranged to make electrical connection with said radial projecting pin. 105 110 115

5. Means for associating a demodulating device, including a plurality of contacts, with a radio receiving system, which comprises a socket including a base portion and a tubular portion, a plurality of radially disposed contact springs in said base portion, arranged to make connection with certain contacts on said demodulating device and an additional contact spring extending vertically from said base portion for making 120 125 130

electrical connection to an additional contact on said demodulating device.

6. A socket for detectors having a plurality of contacts a portion of which are located, aligned, positioned and designed to contact with certain terminals of a detector inserted into said socket, and contacts of which including at least one of the first portion of contacts and at least one other contact are located, aligned, positioned and de-

signed to contact with terminals of a different detector inserted into said socket whereby circuit elements including said socket may conveniently be used with different detectors.

In witness whereof, I hereunto subscribe my name this 6th day of August, A. D., 1921.

FRED W. YOUNG.
